UNITED STATES PATENT OFFICE.

EMIL GROSS, OF WAUWATOSA, AND EDWARD J. BRIKNER, OF MILWAUKEE, WISCONSIN,
ASSIGNORS TO ALLIS-CHALMERS MANUFACTURING COMPANY, OF MILWAUKEE,
WISCONSIN, A CORPORATION OF DELAWARE.

HYDRAULIC TURBINE.

Application filed July 12, 1926. Serial No. 122,026.

This invention relates in general to improvements in hydraulic machines, and relates more specifically to improvements in the construction and operation of actuating mechanism for controlling the flow relative to hydraulic turbine rotors or the like.

An object of the invention is to provide new and useful improvements in the construction and operation of flow control mechanism for hydraulic turbines or the like. Another object of the invention is to provide simple and efficient means for preventing serious damage to turbine structure in cases of abnormal operation of such machines. A further object of the invention is to provide improved inlet guide vane actuating mechanism for hydraulic machines whereby entanglement and possible destruction of linkage is avoided in the event that a portion of such linkage becomes broken. Still another object of the invention is to provide improved means whereby the operation of the shifting or adjusting ring for a series of guide vanes, is not materially affected by the destruction of the connecting elements between one of the vanes and the ring. A further object of the invention is to provide simple and efficient means for limiting the movement of the flow controlling guide vanes of a hydraulic turbine or the like, when a portion of the normal actuating mechanism thereof becomes ineffective.

A clear conception of an embodiment of the invention and of the operation of mechanisms constructed in accordance therewith, may be had by referring to the drawing accompanying and forming a part of this specification in which like reference characters designate the same or similar parts in the several views.

Fig. 1 is a fragmentary central vertical section through the guide vane actuating mechanism of a hydraulic turbine of the Francis type.

Fig. 2 is a fragmentary part sectional top view of a portion of the guide vane actuating mechanism of the turbine illustrated in Fig. 1.

Fig. 3 is a central vertical section through the connection between the two sections of one of the actuating arms for the guide vanes.

The hydraulic turbine specifically illus-

trated in the drawing, comprises in general 55 a bladed rotor 2, a fluid supply conduit 3 for directing fluid inwardly toward the blades of the rotor 2, and an annular series of pivotally supported adjustable inlet guide vanes 4 for directing and for conducting 60 fluid from the supply conduit 3 to the rotor 2. The rotor 2 is disposed within a casing comprising a top cover 5 in which the guide vanes 4 are pivotally supported. Each of 65 the guide vanes 4 has a vertical pivot 6 journaled in the cover 5, and each of the pivots 6 has a sectional actuating arm rigidly attached to the upper extremity thereof. As illustrated, each sectional actuating arm 70 comprises an outer bifurcated section 7 and an inner section 8, the arm sections 7, 8 being connected by means of pins 9, 10. The pins 10 have weakened portions 18 of reduced diameter as clearly shown in Fig. 3, 75 while the pins 9 are of considerably stronger section throughout. The actuating or adjusting ring 12 is journaled upon the turbine casing concentrically of the axis of the rotor 2, and has two superimposed annular 80 series of outwardly extending projections or lugs 14 located between the successive inner ends of the actuating arm sections 8. Links 11 are pivotally connected at one end with the inner ends of the arm sections 8 by means of pins 13, and have their opposite 85 ends pivotally connected to the lugs 14 of the ring 12 by means of pins 15. All of the pins 9, 10, 13, 15 are freely vertically removable upon release of the retaining nuts 90 at the lower extremities thereof, and these pins are freely accessible from the exterior of the casing 5. Each of the outer arm sections 7 has a depending lug 16 formed to coact with adjacent spaced abutments 95 17 on the casing 5, in order to limit the pivotal movement of the corresponding vane 4 in either direction.

During the normal operation of the turbine, fluid under pressure is admitted inwardly toward the rotor 2 from the supply conduit 3 past the adjustable inlet guide vanes 4, and the fluid thus admitted is eventually discharged from the rotor 2 in an axial direction to the usual draft tube located below the unit. The guide vanes 4 may normally be simultaneously adjusted about the axes of their pivots 6, to vary the inlet opening leading to the rotor 2 or to

entirely cut off the flow, by means of a servomotor of ordinary construction cooperating with the revolvable adjusting ring 12. When the ring is shifted about the rotor axis in either direction, motion is simultaneously transmitted to all of the guide vanes 4 through the links 11, the sectional arms, the pivots 6, and the interconnecting pins, thereby causing the vanes 4 to assume any desired position of adjustment.

In case either the opening or the closing movement of one or more of the guide vanes 4 is abnormally obstructed in any manner, the connecting pin 10 of the vane so obstructed will be sheared off or broken at the weakened portions 18, thereby permitting unrestrained normal adjustment of the remaining vanes 4 of the series. When one of the shear pins 10 has been thus broken, the free swinging movement of the corresponding released guide vane 4 is limited by virtue of the engagement between the lug 16 thereof with the adjacent abutments 17 formed on the casing 5. The abutments 17 obviously function to limit undesirable free swinging movement of the vanes 4 in either direction as clearly shown in Fig. 2, and breakage of a pin 10 while the corresponding vane 4 is in opened position, will cause the vane to immediately assume closed position.

When one of the shear pins 10 becomes broken, it may be readily replaced without interrupting the normal operation of the turbine. By providing a pair of pins connecting the arm sections 7, 8 breakage of one of the pins 10 will not permit the elements connecting the ring 12 with the pivots 6 of the disabled vane, to interfere in any manner with the normal operation of the adjacent vanes and with the movement of the actuating ring 12. The entire actuating mechanism is readily accessible from the turbine pit and effectively protects the unit against serious damage in cases of abnormal functioning of one or more of the guide vanes 4.

It should be understood that it is not desired to limit the invention to the exact details of construction and operation herein shown and described, for various modifications within the scope of the claims may occur to persons skilled in the art.

It is claimed and desired to secure by Letters Patent:

1. In combination, a rotor, a movable vane for directing fluid relative to said rotor, a sectional arm for actuating said vane, and a pair of connecting members uniting the sections of said arm, one of said members having a weaker cross section than the other.

2. In combination, a rotor, a movable vane for directing fluid towards said rotor, a sectional arm for actuating said vane, and

a pair of pins connecting the sections of said arm, one of said pins having a weaker cross section than the other.

3. In combination, a rotor, a movable vane for directing fluid relative to said rotor, a sectional arm for actuating said vane, and a pair of pins connecting the sections of said arm, said pins being disposed in an arc concentric with the axis of movement of said vane.

4. In combination, a rotor, a movable vane for directing fluid towards said rotor, a sectional arm for actuating said vane, and a pair of pins connecting the sections of said arm, one of said pins having a weakened section and both of said pins being disposed in an arc concentric with the axis of movement of said vane.

5. In combination, a rotor, a casing for said rotor, a movable vane for directing fluid relative to said rotor, a sectional arm for actuating said vane, one section of said arm having a stop cooperable with said casing for limiting the movement of said vane, and a plurality of pins connecting the sections of said arm, at least one of said pins having a weaker cross section than the other.

6. In combination, a rotor, a casing for said rotor, a movable vane journaled in said casing for directing fluid towards said rotor, a sectional arm for actuating said vane, one section of said arm having a stop cooperable with an abutment on said casing for limiting the movement of said vane, and a pair of pins connecting the sections of said arm, one of said pins having a weaker cross section than the other.

7. In combination, a rotor, a casing for said rotor, a movable vane journaled in said casing for directing fluid towards said rotor, a sectional arm for actuating said vane, one section of said arm having a stop cooperable with an abutment on said casing to limit the movement of said vane, and a pair of pins connecting the sections of said arm, one of said pins having a weakened section and both of said pins being disposed in an arc concentric with the axis of movement of said vane.

8. In combination, a rotor, a movable vane for directing fluid relative to said rotor, a sectional arm for actuating said vane, a pair of pins connecting the sections of said arm, one of said pins having a weakened section, an actuating ring rotatable about the axis of said rotor, and a link connecting said actuating ring with the swinging end of said arm.

9. In combination, a rotor, a movable vane for directing fluid towards said rotor, a sectional arm for actuating said vane, an actuating ring rotatable about the axis of said rotor, means connecting said ring with an end of said arm, and a pair of pins con-

necting the sections of said arm between said arm end and the axis of movement of said vane.

10. In combination, a rotor, a casing for said rotor, a movable vane journaled in said casing for directing fluid towards said rotor, a sectional arm having one end secured to said vane, an actuating ring for said arm, means connecting said ring and the opposite end of said arm, and a pair of pins connecting the sections of said arm intermediate its ends.

11. In combination, a rotor, a casing for

said rotor, a movable vane journaled in said casing for directing fluid towards said rotor, a sectional arm having one section secured to said vane, an actuating ring, means connecting said ring with the other of said arm sections, and a pair of pins connecting said arm sections, at least one of said pins having a weakened portion.

In testimony whereof, the signatures of the inventors are affixed hereto.

EMIL GROSS.

EDWARD J. BRIKNER.
